ELECTRIC DISCHARGE APPARATUS

Finn H. Gulliksen, Pittsburgh, Pa., assignor to Westinghouse Electric & Manufacturing Company, East Pittsburgh, Pa., a corporation of Pennsylvania

Application September 7, 1939, Serial No. 293,731

5 Claims. (Cl. 250—27)

My invention relates to electric discharge apparatus and has particular relation to ignitrons.

In accordance with the teachings of the prior art of which I am aware, an electric discharge valve such as a thyratron is used to control the firing of an ignitron. The thyratron is interposed in circuit with the ignition electrode and the pool of the ignitron and at the instant of firing conducts ignition current through the ignition current through the ignition electrode. Since the ignition current required is of substantial magnitude, the thyratron must necessarily be relatively large. Because of the care which is essential in the construction of a thyratron, the valve is relatively expensive and substantially increases the cost of the equipment.

It is an object of my invention to provide a simple and inexpensive firing system for an ignitron.

Another object of my invention is to provide a firing arrangement of simple structure for an ignitron that shall have all of the advantages of the thyratron.

An ancillary object of my invention is to provide a novel spark gap.

A specific object of my invention is to provide apparatus of simple and inexpensive structure for controlling the supply of alternating current from a source to a load.

More concisely stated, it is an object of my invention to simplify the apparatus used for controlling ignitrons.

In accordance with my invention, the ignition current for an ignitron is supplied through a discharge gap. The gap is interposed in the ignition circuit and conducts current through the igniter when the firing is to take place. I have found that an air gap is particularly adapted for the practice of my invention, although in its broader aspects it may be carried out with a glow discharge gap comprising a plurality of unexcited electrodes disposed in a medium at a pressure which may vary from several millimeters of mercury to a fraction of an atmosphere.

In accordance with the preferred practice of my invention, the spark gap consists of a plurality of main terminals and an ignition terminal disposed adjacent to the main terminals. A spark of a discharge is ignited between the main terminals when a high potential of the order of one thousand to ten thousand volts is impressed between the ignition terminal and the main terminals. The igniter is supplied through the main terminals and the control potential for the apparatus is impressed on the ignition terminal.

The novel features that I consider characteristic of my invention are set forth with particularity in the appended claims. The invention itself, however, both as to its organization and its method of operation, together with additional

objects and advantages thereof, will best be understood from the following description of a specific embodiment when read in connection with the accompanying drawing, in which the single figure is a diagrammatic view showing a preferred embodiment of my invention.

In the drawing, my invention is specifically shown as applied to a resistance welding system in which alternating current is supplied for welding purposes. The apparatus comprises a welding transformer 1 across the secondary 3 of which a pair of welding electrodes 5 are connected. The electrodes are in engagement with a material 7 to be welded, and, when the transformer 1 is energized, current is conducted through the material. The primary 9 of the transformer 1 is supplied from an alternating current source 11 through a pair of ignitrons 13 and 15 interposed in anti-parallel between the source and the primary. The source 11 may be of the usual commercial 60-cycle type. Each ignitron comprises an anode 17, a cathode 19 of the pool type and an ignition electrode 21.

The current for firing the ignitrons 13 and 15 is supplied through a discharge gap 23 which is preferably of the open-air spark type. The gap comprises a pair of principal terminals 25 and 27 and an ignition terminal 29. The principal terminals 25 and 27 are interconnected by a high resistor 31 and are individually connected each to an ignition electrode 21. The ignition terminal 29 is connected to the intermediate tap 33 of the resistor through the secondary 35 of a peaking transformer 37. The potential of the secondary 35 is thus impressed between the ignition terminal 29 and the principal terminals 25 and 27 and the resistor 31 functions to properly distribute it.

The primary 39 of the peaking transformer 37 is supplied through a thyratron 41 of relatively small rating or from a high vacuum valve from a capacitor 43. The capacitor 43 is maintained charged from the source 11 through a suitable rectifier 45 and the polarity of the charge is such that when the thyratron is non-conductive it

impresses a positive potential between its anode 47 and its cathode 49. The control electrode 51 of the thyratron 41 is connected to the cathode 49 in control contactor 53, through a rectifier 55 and a biasing potential 57. The rectifier 55 is supplied from the secondary 59 of another peaking transformer 61. The phase in the half cycles of the source 11 at which the impulses are supplied by the peaking transformer 61 is determined by a rheostat 63 in series with the primary 65 of the transformer. The biasing potential 57 is of such polarity that when the contact 53 is first closed the valve 41 is maintained non-conductive. The rectifier 55 is interposed between the control electrode 51 and the secondary 59 of the transformer 61 in such a sense that an im-

pulse counteracting the biasing potential is supplied during each half period of the source 11. The contact 53 may be the circuit controller of any suitable timing arrangement for welding.

To initiate welding operation, the timing contact 53 is closed. The contact interconnects the control electrode 51 and the cathode 49 of the valve 11, the cathode and the two sources of potential 55 and 57 and, as a result, the valve is rendered conductive at instants predetermined by the setting of the rheostat 63 during each of a number of half periods of the source.

The capacitor 43 in the valve circuit is then discharged through the primary 39 of the first-mentioned peaking transformer 37 and a high potential is impressed through the secondary 35 between the ignition terminal 29 and the main terminals 25 and 27 of the discharge gap 23. The main terminals are connected across the source 11 through the igniters 21 and the cathodes 19 of the main valves 13 and 15. The combined influence of the source potential and the high potential supplied by the peaking transformer 37 is to ignite a discharge or, preferably, a spark between the main terminals. For the purpose of explaining the operation, let us assume that at the instant of ignition of the discharge the upper terminal 67 of the source 11 is positive and its lower terminal 69 negative. Under such circumstances, current flows in a circuit extending from the upper terminal 67 through the primary 9 of the transformer 1, the cathode 19 and the ignition electrode 21 of the right-hand ignitron 15, the spark terminals 25 and 27, the ignition electrode 21 and the cathode 19 of the left-hand ignitron 13, to the lower source terminal 69. The anode-cathode potential of the left-hand ignitron 13 is at this time positive, and, at the same time, the current through its ignition electrode 21 is of the proper polarity to render it conductive. The left-hand ignitron therefore becomes conductive and current flows through the primary 9 of the welding transformer 1.

The ignitron 13 is fired immediately after the discharge gap 23 is ignited. After the ignitron becomes conductive, the potential between its anode 17 and its cathode 19 and therefore the potential across the discharge gap 25-27 and the ignition electrode and cathode of the right-hand ignitron 25, becomes equal to the arc drop potential. Since this potential is relatively small, the current flow through the ignition electrode 21 of the right-hand ignitron 25 and the spark gap 25-27 is materially reduced.

At an interval of the order of the half period of the source 11 later the source polarity reverses and the potential across the left-hand ignitron 13 becomes too small to sustain the discharge and the valve is extinguished. Thereafter another impulse is impressed in the control circuit of the auxiliary valve 41, and the capacitor 43 which was charged while the left-hand ignitron was conductive is again discharged. The spark gap 23 is then again ignited and this time the right-hand ignitron 25 is rendered conductive. The ignitrons thus continue to conduct current alternatingly until the timing contact 53 is opened and the auxiliary valve 41 remains non-conductive.

In the following claims the term "spark-gap" means a pair of terminals separated continually

when in use by a gap in air of substantial length. The term "ignitron" means an electric gaseous discharge tube in which initiation of current flow from anode to cathode is caused by an auxiliary electrode one end of which contacts said cathode.

Although I have shown and described a certain specific embodiment of my invention, I am fully aware that many modifications thereof are possible. My invention, therefore, is not to be restricted except insofar as is necessitated by the prior art and by the spirit of the appended claims.

I claim as my invention:

1. In combination an ignitron having a plurality of principal electrodes and an ignition electrode, means for impressing a potential between said principal electrodes, circuit means having a spark gap interposed therein for supplying ignition current to said ignition electrode, said spark gap having a pair of spark terminals and an ignition terminal, and means for impressing an ignition potential between said ignition terminal and said spark terminals.
2. For use in supplying power from an alternating current source to a load the combination comprising a pair of ignitrons, each having a plurality of principal electrodes and an ignition electrode, interposed in anti-parallel between said source and said load, a spark gap interposed between said ignition electrodes and means for igniting a spark in said gap.
3. For use in supplying power from an alternating current source to a load the combination comprising a pair of ignitrons, each having a plurality of principal electrodes and an ignition electrode, interposed in anti-parallel between said source and said load, a spark gap having a plurality of main terminals and circuit means connecting said terminals between said ignition electrodes.
4. For use in supplying power from an alternating-current source to a load the combination including electric discharge valve means connected in series circuit with said source and load and including a pair of electrodes of the pool type connected through said series circuit to opposite terminals of said source and an ignition electrode in contact with each pool electrode, a spark gap, circuit means connecting said gap between said ignition electrodes, and means for igniting a spark in said gap to effect completion of a circuit between said ignition electrodes.
5. For use in supplying power from an alternating-current source to a load the combination including electric discharge valve means connected in a series circuit with said source and load and including a pair of electrodes of the pool type connected through said series circuit to opposite terminals of said source and an ignition electrode in contact with each pool electrode, a spark gap connected between said ignition electrodes, said gap including a plurality of main terminals and an ignition terminal, and means for impressing a potential between said ignition terminal and said main terminals which is of short duration compared to a half period of said source for igniting a spark in said gap to effect completion of a circuit between said electrodes.

FINN H. GULLIKSEN.
